UNITED STATES PATENT OFFICE.

JOEL HADEN, OF PALMYRA, VIRGINIA.

HARROW.

SPECIFICATION forming part of Letters Patent No. 666,667, dated January 29, 1901.

Application filed September 11, 1900. Serial No. 29,717. (No model.)

To all whom it may concern:

Be it known that I, JOEL HADEN, a citizen of the United States, residing at Palmyra, in the county of Fluvanna and State of Virginia, 5 have invented a new and useful Harrow, of which the following is a specification.

This invention relates to harrows in general, and more particularly to that class comprising an angular frame having rigid teeth 10 extending downwardly therefrom and adapted for engagement with the earth to effect the harrowing operation.

The object of the invention is to provide a construction in which the frame will consist 15 of a number of parts removably connected, so that the shape of the harrow may be varied for different operations, and also in which the parts are hinged together to enable them to adjust themselves to inequalities in the ground, 20 and also to permit raising of the sections to free the teeth from obstructions.

In the drawings forming a portion of this specification, and in which similar numerals of reference designate like and corresponding 25 parts in the several views, Figure 1 is a plan view showing the complete harrow with its weight in place. Fig. 2 is a top plan view showing the harrow in its converted condition. Fig. 3 is a perspective view showing one of 30 the supplemental frames of the harrow. Fig. 4 is a perspective view showing a form of double tooth which is secured at the rear of the central beam. Fig. 5 is a section on line 5 5 of Fig. 1.

Referring now to the drawings, the harrow 35 comprises a central beam 10, at the sides of which are fixed the remaining portions of the harrow, these side portions being duplicates, so that a description of one side suffices for a 40 description of the other.

At each side of the beam 10 and at the forward end thereof is fixed a plate 11, having a 45 perforated outwardly-projecting ear 12 at its rear end. These ears are engaged by hooks 13, fastened upon the outer faces of the front 50 ends of the side members of the harrow. Each of the side members consists of an outside beam 14, which lies at an angle to the central beam 10 and diverges therefrom rear- 55 wardly. To the front end of the beam 14 is fixed a beam 15, which lies parallel to the beam 10 and extends rearwardly somewhat

more than half the distance of the beam 14, 55 said beam 15 being connected adjacent to its rear end to the beam 14 by means of a cross-piece 16. Upon the inner face of the beam 15 and adjacent to each end thereof is fixed a plate 17, having an outwardly-projecting ear 18, said ears being perforated to align with corresponding perforations in the ears 19 of plates 20, fixed to the corresponding face of the beam 10. Through these alining perforations is passed a pintle 21, having a head at one end and a key 22 at the other to prevent its displacement. Thus the beam 14 60 and the parts connected therewith have a hinge connection with the central beam 10 and may be raised and lowered with respect thereto.

In the rear of the cross-piece 16 and between the rear end of the beam 14 and the beam 10 is disposed a truncated triangular frame 23, the outer side of which lies parallel with the beam 14 and the rear side of which is in line with the rear ends of the beams 10 75 and 14. The minor front end 24 of the frame 23 is removably and pivotally connected to the cross-piece 16 through the medium of hooks 26, which engage the eyes 27 of eye-bolts passed through the cross-piece 16. The 80 major rear end 28 of the frame 23 is connected at its outer extremity with the rear end of the beam 14 by means of a metallic strap 29, bolted thereto.

The frame 23 at each side of the beam 10 85 is provided with any desired number of harrow-teeth, as also are the beams 14 and 15 and the cross-piece 16, the harrow-teeth in the cross-piece being shown at 30°. When it is desired to form a rigid harrow, the cross-pieces 16 at opposite sides of the beam 10 are 90 mutually connected by means of a metallic strap 30, passed transversely and beneath the beam 10 and connected with said cross-pieces, as also with the beams 15. The 95 frames 23 are also connected by means of a brace 31, passed through alining staples 32 upon the upper surfaces of the inside beams of the frame and the beam 10, said brace being further held against displacement by bolts 33 100 or by harrow-teeth passed through their connected portions.

In addition to the teeth above mentioned two teeth are attached to the rear end of the

beam 10 in the form of a staple 34, the legs of which pass downwardly at opposite sides thereof to a sufficient extent to enter the earth, the staple being held in place by a bolt 34', passed through perforations 35' in the legs and an alining perforation formed transversely through the beam 10.

Handles for the harrow are provided and consist of two upwardly and rearwardly diverging bars 35, the meeting ends of which are bolted to the beam 10 and the rear ends of which are provided with grips 36. A V-shaped brace 37 is bolted to the beam 10 and has its extremities connected with the portions 35, which latter are further strengthened by means of a cross-brace 38. Chains 39 are each attached at one end to the bars 35 adjacent to the grips 36 and at their opposite ends to the rear ends of the beams 14, supplemental chains 40 being connected with the chains 39 and the rear outer corners of the frames 23 to permit movement of the connected portions of the harrow by means of the handles.

25 When it is desired to use only the frames 23, the beams 14 and 15 and cross-pieces 16 may be removed by withdrawing the pintles 21, unbolting the plates or straps 29, and disengaging the hooks 13, after which a cross-brace 41 is secured to the under side of the beam 10 and extends laterally therefrom to support the front ends of the frames 23. Supports 42, one at each side of the beam 10, are then passed through staples 43, projecting upwardly from the front and rear portions 24 and 28 of the frames 23, and are continued forwardly and convergently to meet and have their meeting ends attached to the beam 10 and secured in any desired manner.

40 It will of course be understood that in practice teeth of any desired kind may be employed and that they may be distributed over the parts of the structure in accordance with any preferred system, and the connecting bolts may be in the form of teeth to perform a double function.

When it is desired to increase the weight of the harrow for more effective operation under certain conditions, such a weight in 50 the form of a log or beam 45 may be placed transversely of the beams 10 and 14 and secured thereon by means of chains or ropes 46, fastened to the ends of the beam or log, and which may be attached to the frame of 55 the harrow in any desired manner.

Having thus described the invention, what is claimed is—

1. A harrow, comprising a central beam, harrow-frames pivotally connected with the central beam and having their outer portions extended rearwardly, and supplemental frames connected with the first-named frames intermediate of their rearwardly-extending portions and the central beam.

2. A harrow, comprising a central beam, harrow-frames pivotally and removably connected with the central beam and having their outer portions extended rearwardly, and supplemental frames connected with the first-named frames and lying between their rearwardly-extended portions and the central beam.

3. A harrow, comprising a central beam, frames pivoted to the central beam and having rearwardly-extended portions, supplemental frames pivoted to the first-named frames and lying between their rearwardly-extending portions and the central beam, handles connected with the central beam, and flexible connections between the handles and the supplemental frames.

4. A harrow, comprising a central beam having perforated ears, frames having hooks engaging certain of said ears, ears upon the frames having perforations alining with the perforations of the corresponding ears upon the central beam, pintles passed through the alining perforations, whereby the frames may be removably connected with the central beam, supplemental frames removably connected with the first-named frames, handles connected with the central beam, and flexible connections between the handles and the frames.

5. A harrow comprising a central beam, frames pivotally and removably connected with the beam, supplemental frames removably connected with the first-named frames, connections between the supplemental frames and the central beam, and brace-receiving means carried by the supplemental frames and disposed to receive and hold braces in position for connection with the central beam.

In testimony that I claim the foregoing as my own I have hereto affixed my signature in the presence of two witnesses.

JOEL HADEN.
